Primary Examiner—Cathy Anne MacCormac

(57) **CLAIM**

The ornamental design for a desktop printer with pass-through paper path, as shown.

DESCRIPTION

FIG. 1 is an overhead perspective view of my design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is an alternate view of FIG. 1.

The broken lines are for purposes of illustration and form no part of the claimed design.
